TREATMENT OF HYDROCARBONS

Gustav Egloff, Chicago, Ill., assignor to Universal
Oil Products Company, Chicago, Ill., a corpora-
tion of Delaware

Application November 30, 1940, Serial No. 368,032

9 Claims. (Cl. 260—683.4)

This invention relates to a process for producing a substantially saturated gasoline of high antiknock value from isoparaffinic hydrocarbons and a normally liquid olefin-containing hydrocarbon fraction. More specifically the invention is concerned with a process which comprises alkylation of normally gaseous and normally liquid isoparaffinic hydrocarbons by olefins present in hydrocarbon fractions of gasoline boiling range produced by cracking, reforming, and polymerization.

A hydrocarbon fraction containing a relatively high proportion of olefins such as a gasoline formed by thermal or catalytic cracking or by other means is inferior for use as aviation fuel because of its high olefin content and its accompanying tendency to oxidize and deposit gum during storage together with the fact that such an olefin-containing fuel has relatively lower antiknock value than is generally desired for aviation purposes. Generally, little improvement in antiknock value is effected by addition of lead tetraethyl to such an olefin-containing fuel. Accordingly it is the purpose of this invention to produce from olefin-containing hydrocarbon fractions and isoparaffinic hydrocarbons relatively high yields of substantially saturated motor fuel of high antiknock value suitable for use in airplane and automobile engines. Further, the antiknock values of these fuels may be increased by moderate additions of lead tetraethyl.

In one specific embodiment the present invention comprises a process for producing a substantially saturated gasoline which comprises commingling an isoparaffinic hydrocarbon fraction with a metallic halide alkylation catalyst in a reactor coil; injecting into said coil at a plurality of points intermediate between its entrance and exit an olefin-containing gasoline and a relatively minor proportion of a hydrogen halide to form a substantially saturated product from isoparaffinic and olefinic hydrocarbons; separating said product into a light fraction comprising essentially unconverted isoparaffinic hydrocarbons and hydrogen halide, a substantially saturated alkylmer gasoline of high antiknock value, and a relatively heavy residue containing metallic halide alkylation catalyst; and recycling said light fraction to commingle with the mixture of isoparaffinic hydrocarbon fraction and metallic halide charged to the process.

A feature of the present invention is the addition of an olefin-containing hydrocarbon fraction at a plurality of points in the reaction coil through which is passed a metallic halide al-

kylation catalyst such as aluminum chloride and a molar excess of an isoparaffinic hydrocarbon at a temperature of from about 0° to about 200° F. under a pressure of from substantially atmospheric to approximately 600 pounds per square inch. A hydrogen halide as hydrogen chloride is also added to the olefin-containing hydrocarbon fraction prior to injection into the mixture of isoparaffin hydrocarbons and metallic halide. 5 Alkylation of isoparaffin with olefins is promoted and undesirable polymerization is substantially avoided when the olefin-containing hydrocarbon fraction is so added at a plurality of points throughout the length of the alkylation reactor. 10 The reaction may thus be carried out so that from about 2 to about 40 molecular proportions of isoparaffin are commingled with each molecular proportion of olefin added thereto.

Addition of a hydrogen halide as hydrogen chloride to the reaction mixture in an amount of from between about 0.5 to about 15% by weight thereof not only promotes the alkylation activity of the metallic halide catalyst but also tends to progressively restore alkylation activity to the used metallic halide catalyst as it passes through the alkylation reactor. As the mixture of isoparaffins, olefins, and metallic halide catalyst enters the reactor, relatively little hydrogen halide is present, but as the reaction mixture continues in its passage through the alkylation reactor the hydrogen halide concentration increases progressively. The resulting reaction product is separated into a mixture of hydrogen halide and unconverted isoparaffins, a substantially saturated alkylate of gasoline boiling range, and a sludge or residue containing the metallic halide catalyst. 20 At least a portion of said mixture of hydrogen halide and unconverted isoparaffins is recycled to commingle with the mixture of freshly added isoparaffin hydrocarbons and metallic halide being charged to the alkylation reactor. After the process is in operation, the hydrogen halide which is continuously commingled with the charged olefin-containing fraction is sufficient to replace 25 the hydrogen halide lost from the system. The catalyst of the Friedel-Craft type employed which consists of a halide or a mixture of halides, preferably the chlorides, of aluminum, zinc, iron, zirconium, copper, etc., is used in an amount of from about 1 to about 15% by weight of the hydrocarbons present in the alkylation zone.

The different alkylation catalysts which may be used alternatively for promoting the process of this invention are not necessarily equivalent 30 in their action and the conditions of temperature,

pressure, and time employed in any given alkylation are determined by the catalyst, the composition of the reaction mixture, and by other factors.

For the purpose of illustrating the combination of steps characteristic of the present invention, the accompanying drawing illustrates diagrammatically means embodying one specific apparatus utilizable for producing gasoline of high antiknock value from isoparaffinic hydrocarbons and normally liquid olefin-containing fractions as may be produced by cracking, reforming, and polymerization.

Referring to the drawing, a mixture of aluminum chloride and of an isoparaffin hydrocarbon or of an isoparaffin hydrocarbon fraction is introduced through line 1 and valve 2 to pump 3 which discharges through line 4 and valve 5 into coil 6 provided with jacket 7 through which a heating or cooling medium may be circulated by way of lines 8 and 9 in order to maintain an alkylation temperature in coil 6. Simultaneously and continuously an olefin-containing gasoline, such as may be formed by cracking, reforming, and polymerizing treatments, is admitted through line 10 and valve 11 to pump 12 which discharges through header 13 containing valves 14 and 15. Hydrogen chloride from an outside source is directed through line 16 and valve 17 to pump or compressor 18 which discharges through line 19 and valve 20 into header 13, already mentioned.

From header 13 the olefin-containing gasoline is introduced through branch lines 21 and 22 containing valves 23 and 24 to intermediate points of coil 6 which contains the aluminum chloride-isoparaffin mixture as already described. The commingled mixture of olefin-containing hydrocarbon fractions and hydrogen chloride, the latter also present in at least a portion of header 13, is directed therefrom through branch lines 25 and 26, provided respectively with valves 27 and 28, to coil 6, already mentioned. Header 13 also communicates with coil 6 through valve 15. As hereinabove set forth, the olefin-containing hydrocarbon fraction may be introduced to the aluminum chloride-isoparaffin mixture in coil 6 at a plurality of points, indicated diagrammatically as 5 in the accompanying drawing, although any plurality of points of injection for olefin and hydrogen chloride may be employed. The hydrogen chloride and olefin-containing fraction may be introduced together or separately to the reaction coil.

From coil 6 the alkylation mixture which is substantially free from olefinic hydrocarbons is directed through valve 29 and line 30 to fractionator 31 of conventional design adequate to separate a light fraction comprising essentially an unconverted hydrocarbon fraction and hydrogen chloride, a substantially saturated alkylate, and a residue or sludge containing aluminum chloride catalyst employed in the alkylation. While a major proportion of the alkylation reaction occurs during contact of the hydrocarbons with the catalyst in reactor 6, this conversion may reach completion in the lower portion of fractionator 31, from the top of which a light fraction comprising essentially an unconverted isoparaffin fraction and hydrogen chloride is directed through line 32 and valve 33 to pump 34 which discharges through line 35 and valve 36 into the entrance end of coil 6 employed as a reactor for alkylation of isoparaffin hydrocarbons with olefins. A portion of the light fraction passing

through line 32 is directed therefrom to waste, storage, or other use through line 37 and valve 38. The substantially saturated alkylate of high antiknock value is directed from fractionator 31

- 5 through line 39 containing valve 40 to cooling and storage, not shown in the diagrammatic drawing. The residue or sludge containing the aluminum chloride catalyst is withdrawn from the bottom of fractionator 31 through line 41 and valve 42
- 10 to storage or to other use, not shown. Also a portion of said sludge containing used aluminum chloride may be returned to coil 6 by means not shown to therein assist in the alkylation of isoparaffins with olefins.
- 15 The following example is introduced to show results normally expected in the operation of the process although with no intention of unduly limiting the generally broad scope of the invention:
- 20 5 molecular proportions of isobutane having dispersed therein about 10% by weight of finely divided anhydrous aluminum chloride is passed through a reaction coil maintained at 150° F., to which is added one molecular proportion of a cracked gasoline containing approximately 30% by weight of normally liquid olefins. The cracked gasoline is commingled with about 4% by weight of hydrogen chloride and the resulting mixture is introduced at different points in said reaction coil intermediate between its entrance and exit
- 25 ends in order to catalyze alkylation and to substantially avoid polymerization of olefins contained in said gasoline. The alkylation of isobutane by the normally liquid olefins present in said cracked gasoline converts said olefins and a portion of the added isobutane into a substantially saturated alkylate recoverable in admixture with the saturated constituents of the cracked gasoline charged. Thus the total yield of substantially saturated motor fuel is approximately 125% by weight of the cracked gasoline charged to the process.
- 30
- 35
- 40

The character of the present invention and its novelty and utility in producing substantially saturated motor fuel from olefin-containing gasoline and added isoparaffin hydrocarbons can be seen from the preceding specification and example given, although neither section is intended to limit unduly the generally broad scope of the process.

I claim as my invention:

1. A process for producing a substantially saturated gasoline which comprises commingling an isoparaffinic hydrocarbon fraction with a metallic halide alkylation catalyst in a reactor coil; injecting into said coil at a plurality of points intermediate between its entrance and exit ends an olefin-containing gasline and a relatively minor proportion of a hydrogen halide to form a substantially saturated product; separating said product into a light fraction comprising essentially unconverted isoparaffinic hydrocarbons and hydrogen halide, a substantially saturated alkymer gasoline of high antiknock value, and a relatively heavy residue containing metallic halide alkylation catalyst; and recycling said light fraction to commingle with the mixture of isoparaffinic hydrocarbon fraction and metallic halide charged to the process.
  - 55
  - 60
  - 65
  - 70
  - 75
2. A process for producing a substantially saturated gasoline which comprises commingling an isoparaffinic hydrocarbon fraction with aluminum chloride in a reactor coil; injecting into said coil at a plurality of points intermediate between its entrance and exit ends an olefin-containing

gasoline and a relatively minor proportion of hydrogen chloride to form a substantially saturated product; separating said product into a light fraction comprising essentially unconverted isoparaffinic hydrocarbons and hydrogen chloride, a substantially saturated alkymer gasoline of high antiknock value, and a relatively heavy residue containing aluminum chloride; and recycling said light fraction to commingle with the mixture of isoparaffinic hydrocarbon fraction and aluminum chloride charged to the process.

3. A process for producing a substantially saturated gasoline which comprises commingling an isoparaffinic hydrocarbon fraction with aluminum chloride and another metal chloride of the Friedel-Crafts type in a reactor coil; injecting into said coil at a plurality of points intermediate between its entrance and exit ends an olefin-containing gasoline and a relatively minor proportion of hydrogen chloride to form a substantially saturated product; separating said product into a light fraction comprising essentially unconverted isoparaffinic hydrocarbons and hydrogen chloride, a substantially saturated alkymer gasoline of high antiknock value, and a relatively heavy residue containing the metallic chloride alkylating catalyst mixture; and recycling said light fraction to commingle with the mixture of isoparaffinic hydrocarbon fraction and metallic chlorides charged to the process.

4. A process for producing a substantially saturated gasoline which comprises commingling an isoparaffinic hydrocarbon fraction with aluminum chloride and another metal chloride of the Friedel-Crafts type in a reactor coil maintained at a temperature between about 0° and about 200° F., injecting into said coil at a plurality of points intermediate between its entrance and exit ends an olefin-containing gasoline and a relatively minor proportion of hydrogen chloride to form a substantially saturated product; separating said product into a light fraction comprising essentially unconverted isoparaffinic hydrocarbons and hydrogen chloride, a substantially saturated alkymer gasoline of high antiknock value, and a relatively heavy residue containing the metallic chloride alkylating catalyst mixture; and recycling said light fraction to commingle with the mixture of isoparaffinic hydrocarbon fraction and metallic chlorides charged to the process.

5. A process for producing a substantially saturated gasoline which comprises commingling an isoparaffinic hydrocarbon fraction with between about 1% and about 15% by weight of aluminum chloride in a reactor coil; injecting into said coil at a plurality of points intermediate between its entrance and exit ends an olefin-containing gasoline and a relatively minor proportion of hydrogen chloride to form a substantially saturated product; separating said product into a light fraction comprising essentially unconverted isoparaffinic hydrocarbons and hydrogen chloride, a substantially saturated alkymer gasoline of high antiknock value, and a relatively heavy residue containing aluminum chloride; and recycling said light fraction to commingle with the mixture of isoparaffinic hydrocarbon fraction and aluminum chloride charged to the process.

6. A process for producing a substantially saturated gasoline which comprises commingling an isoparaffinic hydrocarbon fraction with between about 1% and about 15% by weight of aluminum

chloride in a reactor coil; injecting into said coil at a plurality of points intermediate between its entrance and exit ends an olefin-containing gasoline and between about 0.5 and about 15% by weight of hydrogen chloride to form a substantially saturated product; separating said product into a light fraction comprising essentially unconverted isoparaffinic hydrocarbons and hydrogen chloride, a substantially saturated alkymer gasoline of high antiknock value, and a relatively heavy residue containing aluminum chloride; and recycling said light fraction to commingle with the mixture of isoparaffinic hydrocarbon fraction and aluminum chloride charged to the process.

7. A process for producing a substantially saturated gasoline which comprises commingling an isoparaffinic hydrocarbon fraction with between about 1% and about 15% by weight of a mixture of aluminum chloride and another metal chloride of the Friedel-Crafts type in a reactor coil maintained at a temperature between about 0° and about 200° F.; injecting into said coil at a plurality of points intermediate between its entrance and exit ends an olefin-containing gasoline and between about 0.5 and about 15% by weight of hydrogen chloride to form a substantially saturated product; separating said product into a light fraction comprising essentially unconverted isoparaffinic hydrocarbons and hydrogen chloride, a substantially saturated alkymer gasoline of high antiknock value, and a relatively heavy residue containing the metallic chloride alkylating catalyst mixture; and recycling said light fraction to commingle with the mixture of isoparaffinic hydrocarbon fraction and metallic chlorides charged to the process.

8. A process for producing a substantially saturated gasoline which comprises commingling between about 2 and about 40 molecular proportions of an isoparaffinic hydrocarbon fraction with between about 1% and about 15% by weight of aluminum chloride in a reactor coil; injecting into said coil at a plurality of points intermediate between its entrance and exit ends from about 0.5 to about 15% by weight of hydrogen chloride based upon the isoparaffinic hydrocarbons and a gasoline containing about 1 molecular proportion of olefinic hydrocarbons to form a substantially saturated product; separating said product into a light fraction comprising essentially unconverted isoparaffinic hydrocarbons and hydrogen chloride, a substantially saturated alkymer gasoline of high antiknock value, and a relatively heavy residue containing aluminum chloride; and recycling said light fraction and at least a portion of said heavy residue containing aluminum chloride to commingle with the mixture of isoparaffinic hydrocarbon fraction and aluminum chloride charged to the process.

9. A process for producing substantially saturated gasoline which comprises commingling a low boiling isoparaffinic fraction with a metal halide alkylating catalyst, passing the resultant mixture in a restricted stream through a reaction zone maintained under alkylating conditions, introducing to said stream at a plurality of spaced points in its path of travel through the reaction zone a hydrogen halide and olefinic hydrocarbons, boiling in the gasoline range, and fractionating the effluent of said zone to separate gasoline fractions therefrom.

GUSTAV EGLOFF.
